United States Patent Office.

PETER LOCKIE, OF ROCHESTER, NEW YORK.

Letters Patent No. 99,450, dated February 1, 1870.

IMPROVED WASHING-MACHINE.

The Schedule referred to in these Letters Patent and making part of the same.

To all whom it may concern:

Be it known that I, PETER LOCKIE, of the city of Rochester, in the county of Monroe, and State of New York, have invented a certain new and useful Improvement in Washing-Machines; and I do hereby declare that the following is a full and exact description thereof, reference being had to the accompanying drawings, making part of this specification, in which—

Figure 1 represents a longitudinal vertical section; and

Figure 2, a section of a portion of the cylinder at right angles to fig. 1.

Like letters of reference indicate corresponding parts in both figures.

My invention consists in combining with the cylinder of a washing-machine, a series of radial slats on the sides of the cylinder, converging or widening as they extend from the centre outward, so as to form a wedging space within, which concentrates the clothes, and gives the maximum degree of agitation; also, in the further arrangement of the box for discharging the dirt, and attaching a wringing-machine, the whole as hereinafter set forth.

In the drawings—

A indicates the box of the washing-machine; and B, the washing-cylinder, mounted therein, and receiving motion by means of crank *a*, and gears *b c*, or any equivalent arrangement.

In the present case, I form a rim, *r*, on the side of the cylinder, and have a friction-wheel, *b*, in contact therewith, whereby motion may be communicated to the cylinder.

It is desirable to dispense with toothed wheels and rims, owing to the liability of metals to rust, and of wood to swell.

In general features, the cylinder may be of any desired construction, but I prefer that shown in the drawings, in which it is formed with closed sides *d d*, and open rounds or bars *f f f*.

On the inner faces of the sides *d*, I secure radial slats or rollers *g g*, either stationary or revolving, extending from the centre to periphery, as shown.

These slats gradually widen or increase in projection from the sides *d*, as they extend from the centre to periphery, as indicated in fig. 2, thereby leaving a wedging space, *h*, near the periphery, which concentrates the clothes in a close mass.

Loose balls *i i* are employed, as in some other machines, for giving additional action.

The special feature of novelty in this portion of my invention is the employment of these slats, the effect being to concentrate the clothes in the wedging space as they are carried around, and fall back, thereby producing a squeezing-action, and driving the water

through with great force by the concentration. This effect cannot be produced where the slats are dispensed with, as in that case the force of the water is diffused, and the clothes do not present themselves in the best position for action.

In addition to the above, this arrangement of the slats is such as to raise the water and discharge it upon the clothes in the most effective manner. It starts imperceptibly and in a body, at the centre, but the widening of the slats diffuses it into many currents, which discharge in an angular direction into the wedging space, thereby driving through the clothes with great force, and meeting and converging, so as to produce great agitation.

The same effect is also produced on the balls, the gradual inward-incline driving them down in an angular direction, to produce an intense pounding.

In the angle *s*, at the bottom of box *A*, is a discharge-orifice, *k*; and above this, and near the periphery of the cylinder, is a perforated false bottom, *l*, as clearly shown in fig. 1.

The dust and sediment extracted from the clothes, settles down through this bottom into the still space below, and, from the peculiar angular form of the chamber, and its remoteness from the cylinder, is prevented from rising again in a body, to contaminate the clothes, as would be the case were the space open. This arrangement of the false bottom, covering the angular space, I believe to be new.

At one end of the box, on the inside, is situated a cross-cleat, *m*, having a free space, *n*, between it and the end of the box, and a discharge-opening, *p*, at the bottom, leading back into the interior of the box.

This arrangement is for the attachment of a wringing-machine, the expressed water from which runs down space *n*, and escapes through opening *p*, into the interior of the box again, thereby preventing over discharge. This feature I also believe original with myself.

What I claim as my invention, and desire to secure by Letters Patent, is—

The combination and arrangement, in a washing-machine, of the cylinder, with internal radial slats *g*, the peripheral rounds *f*, forming a wedging space, as shown, the box *A*, with perforated bottom *b*, overhanging the angular space *s*, and the cleat *m*, with space *n*, and return-passage *p*, when the parts are constructed and operate as described and shown.

In witness whereof, I have hereunto signed my name, in the presence of two subscribing witnesses.

PETER LOCKIE.
